REVERSIBLE DIE BLOCK

Richard E. Lang, 100 Grienbriar Drive, Carnegie, Pa.
Filed June 11, 1964, Ser. No. 374,322
13 Claims. (Cl. 83—640)

This invention relates to a die block useful in punch presses and the like, and more particularly to a reversible die block which may be rotated so as to accept structural members in either of two positions for piercing openings therethrough.

As is known, punch presses are employed to pierce openings in structural members, such as H-beams and I-beams. The press includes a punch bit and a die having a die opening adapted to receive the punch bit. The punch bit is powered toward and into the die during the piercing operation and is retracted in the opposite direction.

Many attempts have been made to design a die block which will accept structural members of various shapes and sizes. One such die block includes an upper die portion and a lower die portion. The upper die portion is used to punch openings in the web portion of structural members while the lower die portion is used to punch openings in the flange portions of the structural members. Because of the difference in elevation between the upper and lower die portions, it was necessary to lower the punch bit for use with the lower die portion and then to raise the punch bit for use with the upper die portion. Furthermore, the stripper, employed to retain the structural member in a fixed position during retraction of the punch bit, also had to be relocated along with the punch bit. This is an unsatisfactory arrangement, since, it is very time consuming and adds to the cost of fabrication.

Accordingly, it is the principal object of the present invention to provide a novel die block for use with a punch bit for piercing openings in structural elements.

Another object of the present invention is to provide a novel die block which will accept structural members of various configurations and sizes.

Still another object of the present invention is to provide a novel die block adapted to pierce openings in the web portion and in the flange portions of structural members without requiring a change in the position of the punch bit.

Another object of the present invention is to provide a die block for use in a punch press, which permits the structural elements to be moved freely for piercing openings at various locations thereon.

A further object of the present invention is to provide a die block having a novel configuration including an L-shaped recess which is adapted to receive, for example, the flange of an I-beam during piercing of openings in the flanges or web of the I-beam.

In accordance with the present invention, there is provided a novel die block comprising a base portion having an arm portion projecting from one surface thereof. The arm portion serves as the die and includes a pair of intersecting surfaces each of which is provided with a die opening extending perpendicularly therethrough. The die block is mounted for rotation about an axis which is inclined with respect to the central longitudinal axis of a punch bit. The rotational axis about which the die block rotates is offset from the central axis of the punch bit. The die openings in the arm portion are equidistantly spaced from the rotational axis of the die block. The arrangement is such that in one position of the die block, the arm portion is generally parallel with the central axis of the punch bit and has its associated die opening aligned with the punch bit. The die block may be rotated to a second position wherein the arm portion extends

2

transversely of the central axis of the punch bit and has its associated die opening aligned with the punch bit.

In the present die block, the die openings preferably are spaced from the rotational axis in order to minimize the stress concentrations to which the die is subjected during a punching operation. Alternatively, a combination or two-way die could be fabricated wherein the die openings intersect one another and the rotational axis of the die block. In this arrangement, the central axes of the die openings, the central axis of the punch bit and the rotational axis of the die block reside in a common plane.

The arm portion projects from one surface of the base portion and cooperates therewith to define an inset L-shaped recess which is adapted to receive, for example, the flange of an I-beam. The arrangement is such that when the present die block is in one position, that surface of the arm portion which is opposite the punch bit is adapted to be engaged by the web portion of an I-beam for piercing openings therein. Conversely, when the die block is in the second position, that surface of the arm portion which is opposite the punch bit is adapted to be engaged by one of the flanges of the I-beam for piercing openings therein.

It will become apparent later in the specification, that each of the intersecting surfaces when disposed in opposition to the punch bit will be disposed at the same distance from the punch bit. This design eliminates the high and low die block changes as well as the punch stem and stripper position changes which were necessary in the punch presses heretofore available.

The present die block also is provided with locating means which serves to align the die block in either of the first or second position whereby the appropriate one of the die openings is aligned with the punch bit. This design eliminates the need to realign each of the die openings with respect to the punch bit after each rotational changeover.

In the drawings accompanying this specification, the present die block is illustrated wherein the rotational axis is inclined at an angle of 45° with respect to the central axis of the punch bit. In this showing the aforementioned intersecting surfaces are mutually perpendicular with the rotational axis of the die block extending through a point on the line of intersection of these surfaces. Furthermore, the die openings also are mutually perpendicular. It is to be understood, however, that it is within the scope of the present invention that the rotational axis be inclined at angles other than 45°.

It should also be noted that a simple, manual method is shown for aligning the die block in either of the first or second position and for securing the die block in place. It will be readily apparent to those skilled in the art that numerous other methods may be employed for aligning the die block, for securing the die block and for rotating the die block into either the first or second position. For example, each of these operations may be performed by automatic mechanisms well known in the art today.

The above and other objects and advantages of the present invention will become apparent from the following detailed description by reference to the accompanying drawings, in which:

FIGURE 1 is a side view of a conventional punch press provided with the die block of the present invention;

FIG. 2 is a fragmentary front view of the present die block illustrating the relative positions of the die openings and a punch bit;

FIG. 3 is a fragmentary side view illustrating the present die block in a first position, with portions cut away to show details;

FIG. 4 is a fragmentary side view illustrating the present die block in a second position, with portions cut away to show details; and

FIG. 5 is a fragmentary cross-sectional view illustrating an alternative embodiment of an arm portion of the present die block.

Reference is now directed to FIG. 1, wherein there is illustrated a punch press generally indicated by the numeral 10. The punch press 10 includes a C-shaped frame 12 having an upper arm 14 and a lower arm 16 and a power section 18 at the rear of the C-shaped frame 12. At the forward end of the upper arm 14 there is provided a housing 20 which supports a punch slide 22 for reciprocal movement in a vertical direction. A punch bit 24 is secured to the punch slide 22 and is moved along its central longitudinal axis 25. The power section 18 supplies the necessary power, through a conventional gear arrangement, to forcibly lower the punch bit 24 for piercing openings in, for example, the I-beam 26, and for elevating the punch bit 24 into a retracted position.

At the forward end of the lower arm 16 there is provided a reversible die block 28 of the present invention. The reversible die block 28 is shown in a first of two positions. In this position, the reversible die block 28 cooperates with the punch bit 24 for piercing openings in the web 30 of the I-beam 26. As will be described, the reversible die block 28 may be rotated into a second position which will permit openings to be pierced in the flange portions 32 of the I-beam 26.

Reference is now directed to FIGS. 2-4, inclusive, for a detailed description of the present die block 28. The die block 28 includes a base portion 34 and an arm portion 36 which projects from the base portion 34 and serves as the die portion of the die block 28, as will be described.

BASE PORTION 34

As can best be seen in FIGS. 3 and 4, the base portion 34 is generally triangular in shape and has a first face 38 engaged over an inclined surface 40 provided on the lower arm 16 of the C-shaped frame 12. A shear pin 42 is located at the center of the first face 38 and extends into the base portion 34 of the die block 28 and into the lower arm 16 of the C-shaped frame 12. The shear pin 42 defines a rotational axis, indicated by the dash-dot line 44, about which the die block 28 is rotatable. The rotational axis 44 is perpendicular to the inclined surface 40 and extends therefrom toward the punch bit 24. The rotational axis 44 is inclined with respect to the central axis 25 at an angle indicated at A in FIG. 4. In the drawings, the angle A is 45°.

In FIG. 3, the die block 28 is illustrated in a first position, designated by the Roman numeral I, into which the die block 28 may be rotated. In FIG. 4, the die block 28 is illustrated in a second position, indicated by the Roman numeral II, into which the die block 28 may be rotated. From the first to the second position and vice versa, the die block 28 is rotated through 180°.

As can best be seen in FIGS. 2-4, inclusive, the base portion 34 is provided with a pair of diametrically opposite openings 46, 48 formed adjacent to the first face 38. The openings 46, 48 comprise portions of a locating means 50 which serves to align the die block 28 in the first position I and the second position II. As stated above, the locating means 50 may be manually or automatically operated. As illustrated herein, however, the locating means 50 is manually operated and comprises a locating pin 52 which rides in a groove 54 formed in the forward vertical face of the lower arm 16. The pin 52 is movable vertically in alignment with the rotational axis 44, for example, into the opening 46 to lock the die block 28 in the first position I. Conversely, when the die block 28 is rotated into the second position II, the locating pin 52 will be introduced into the

opening 48. The die block 28 may be secured in either of the first or second position I, II, by any suitable means, such as a plurality of bolts 56 which extend through a peripheral flange 58 formed in the base portion 34 and are threadedly engaged in the lower arm 16 of the C-shaped frame 12.

ARM PORTION 36

The arm portion 36 is generally rectangular in shape and includes a pair of intersecting faces 60, 62 which in this embodiment are mutually perpendicular. Divergently extending die openings 64, 66 are provided, one each in each of the faces 60, 62, respectively. The die openings 64, 66 are mutually perpendicular and equidistantly spaced from the rotational axis 44. Furthermore, the die openings 64, 66 are positioned on opposite sides of the rotational axis 44. As can be seen in FIG. 2, the rotational axis 44 is offset or spaced from the central axis 25 by a distance indicated at 67. The overall arrangement is such that when the die block 28 is in the first position I, as in FIG. 3, the die opening 64 is aligned with the punch bit 24 and cooperates therewith during piercing of openings in the web 30 of the I-beam 26; and when the die block 28 is in the second position II, as in FIG. 4, the die opening 66 is aligned with the punch bit 24 and cooperates therewith during piercing of openings in the flange portions 32 of the I-beam 26.

The arm portion 36 extends in cantilever beam relation from a face 68 of the base portion 34. Hence, the arm portion 36 and the face 68 cooperate to form an L-shaped recess 70 which receives one of the flange portions 32 of the I-beam 26, the arrangement being such that different sized I-beams may be engaged with the die block 28, in those positions illustrated in FIGS. 3 and 4.

The L-shaped recess 70 permits the I-beam 26 to be moved laterally of the die block 28 for piercing openings at various locations in the web 30 and the flange portions 32 of the I-beam 26. For example, as can be seen in FIG. 3, the I-beam 26 may be moved laterally, to the right or to the left of FIG. 3, so that openings may be pierced at different locations in the web 30. Similarly, as can be seen in FIG. 4, the I-beam 26 may be moved laterally, to the right or to the left of FIG. 4, so that openings may be pierced at various locations in the flange portions 32 of the I-beam 26.

The face 60, in FIG. 3, extends transversely of the central axis 25 of the punch bit 24 and is spaced from the end of the punch bit 24 by a predetermined distance indicated by 72. When the die block 28 is rotated into the second position II, as illustrated in FIG. 4, the face 62 of the arm portion 36 also is spaced from the end of the punch bit 24 by the same distance 72. Consequently, the punch bit 24 is always at the correct distance from each of the die openings 64, 66. That is to say, there is no need for repositioning the punch bit 24 with respect to the die openings 64, 66 as was heretofore necessary in conventional punch presses.

ALTERNATIVE EMBODIMENT

Reference is now directed to FIG. 5 wherein there is illustrated an alternative embodiment of the arm portion designated by the numeral 36'. Corresponding numerals will be employed to identify corresponding parts already described.

The arm portion 36' is provided with the pair of divergently extending die openings 64, 66, one each in each of the intersecting faces 60, 62, respectively. In this embodiment, however, the die openings 64, 66 intersect within the arm portion 36', the arrangement being such that the central axis 25 of the punch bit 24, the rotational axis 44, and the central axes of the die openings 64, 66 reside in a common plane, i.e., the plane of the drawing.

DESIGN CONSIDERATIONS

As stated above, the rotational axis 44 may be inclined with respect to the central axis 25 at angles other than 45°. The inclination of the rotational axis 44 is dependent on the load requirements of the die block 28. For example, if the angle A (FIG. 4) is 40°, the length of the arm portion 34 will be shorter so that a larger load may be supported. Conversely, if the angle A (FIG. 4) is 50°, the arm portion 34 will be longer so that a lighter load may be supported. In any event, the die block 28 will have the same general configuration illustrated in the drawings.

Although the present invention has been illustrated in connection with one specific embodiment, it will be readily apparent to those skilled in the art that various changes in form and arrangement of parts to suit requirements may be made without departing from the spirit and scope of the present invention.

I claim as my invention:

1. In a punch press having a frame, a punch bit supported on said frame for reciprocal movement along its central axis, and means for powering said punch bit in one direction to pierce an element and for retracting said punch bit in the opposite direction, the improvement comprising: a die block supported on the base of said frame for rotation about an axis which is inclined with respect to said central axis, said rotational axis extending from the base of said frame toward said punch bit; said die block including an arm portion having a pair of divergently extending die openings; said die block being rotatable about said rotational axis from a first position wherein one of said die openings is aligned with said punch bit to a second position wherein the other of said die openings is aligned with said punch bit; and means for maintaining said die block in said first and second positions.

2. The improvement of claim 1 wherein said die openings are formed on opposite sides of said rotational axis.

3. The improvement of claim 1 wherein said die openings are aligned and intersect; the central axes of said die openings, said central axis of said punch bit and said rotational axis residing substantially in a common plane.

4. The improvement of claim 1 wherein said rotational axis lies in a plane which extends parallel to said central axis and is spaced therefrom.

5. The improvement of claim 1 wherein said central axis is perpendicular to a surface of said arm portion when each of said die openings is disposed opposite to said punch bit.

6. The improvement of claim 1 including locating means operatively connected with said base for aligning said die in said first and second positions prior to securing in said positions.

7. The improvement of claim 1 wherein each of said die openings is disposed at the same distance from the end of said punch bit when positioned opposite thereto.
8. In a punch press having a frame, a punch bit supported on said frame for reciprocal movement along its central axis, and means for powering said punch bit in one direction to pierce an element and for retracting said punch bit in the opposite direction, the improvement comprising: a die block including a base portion and an arm portion which projects from said base portion; said base portion being mounted on an inclined surface of said frame for rotation about a rotational axis which is perpendicular to said inclined surface and extends toward said punch bit; said arm portion having a pair of intersecting faces each of which is positionable transversely of said central axis in opposition to said punch bit; said arm portion having die openings extending therethrough, at least one in each of said intersecting faces, said die block being rotatable about said rotational axis from a first position wherein one of said die openings is aligned with said punch bit to a second position wherein the other of said die openings is aligned with said punch bit; and means for maintaining said die block in said first and second positions.
9. The improvement of claim 8 wherein said die block is rotated through 180° from said first position to said second position.
10. The improvement of claim 8 including a shear pin aligned coaxially with said rotational axis, said shear pin extending through said inclined surface into said base portion and said frame portion; said die block being rotatable on said shear pin.
11. The improvement of claim 8 including locating means for aligning said die block in said first and second positions prior to securing in said positions.
12. The improvement of claim 11 wherein said locating means comprises a locking pin carried in a keyway formed in said frame, said locking pin being positioned to extend into a first opening formed in said base portion for locking said die block in said first position and for extending into a second opening formed in said base portion for locking said die block in said second position.
13. The improvement of claim 8 wherein said arm portion projects in cantilever beam relation from one face of said base portion, said arm portion cooperating with said one face to define a generally L-shaped recess adapted to receive portions of the element being punched which extend toward said base portion.
